Patented Nov. 27, 1917.

GRANT E. ALLEMAN,

Inventor

By

Grant E. Allemans
Attorney

UNITED STATES PATENT OFFICE.

GRANT E. ALLEMAN, OF SHOEMAKERSVILLE, PENNSYLVANIA.

DREDGING DEVICE.

1,248,052.

Specification of Letters Patent. Patented Nov. 27, 1917.

Application filed August 25, 1917. Serial No. 188,097.

To all whom it may concern:

Be it known that I, GRANT E. ALLEMAN, a citizen of the United States, residing at Shoemakersville, in the county of Berks and State of Pennsylvania, have invented certain new and useful Improvements in Dredging Devices, of which the following is a specification.

This invention relates to improvements in dredging devices and it is intended more particularly for use in dredging streams for the reclaiming of coal from culm.

The invention comprises a pair of floats, one of which is stationary, preferably anchored and the other of which is attached to the stationary float through the medium of a pivotal connection, whereby the movable float, on which the suction device or dredging machinery is located, may be moved about within a certain radius, whereby a large area of river bottom may be worked without moving from the anchored point.

Provision is made in the present invention for conveying the coal thus reclaimed from the movable float to the stationary float, from which latter it may be raised by any suitable device and delivered to the wharf, on cars or to any desired point.

Provision is also made for carrying off the refuse that is deposited while the culm is drifting from the movable float to the stationary float, thus removing this refuse to a point where it will not again be drawn up by the pump.

The invention is more fully described in the following specification and clearly illustrated in the accompanying drawing, in which:

Figure 1 is a plan view of my improved dredging device.

Fig. 2 is a side elevational view thereof.

Fig. 3 is a detail view, slightly enlarged, of one of the pivotal connections between the two floats.

The numeral 1 designates the stationary float, which may be secured to the wharf or other point in any desired manner. This float is provided with an elevating device, of any desired form, preferably that of an endless belt provided with a series of vanes, indicated by the numeral 3. This elevating device is operated by means of a suitable motor indicated by the numeral 4.

The elevating belt travels in a trough 5, one end of which projects beyond the end of

the float whereby the coal when drawn to the top thereof may be deposited in cars or other receptacles. The other end of the trough projects beyond the opposite end of the float and is provided with an upwardly extending tubular member 6, forming an entrance into the trough.

The numeral 2 designates the movable float, and on this float I provide a dredging or suction device of any well known form, as for instance a power driven pump, 7 provided with an elongated outlet tube 8.

The numeral 9 designates a coal washing chute of any desired form, arranged at an incline to the surface of the float, whereby the coal or culm deposited therein will drift toward the lower end while the finer particles together with the waste water will pass through openings in the bottom thereof. The numeral 10 designates a refuse trough, located immediately beneath the washing chute and adapted to receive said refuse and water.

The ends of both the washing chute and the refuse trough project beyond the end of the float, and each of these members is formed with a downwardly projecting tubular member 11, the tubular member on the washing chute being adapted to enter the tubular member 6 on the end of the trough 5, as clearly shown in Fig. 3, thereby forming a pivotal connection between the two floats and permitting the float 2 to be moved in a semi-circular path around its connection with the stationary float.

The refuse trough 10 is also provided with a tubular member 11, adapted to enter a like member 12 on a conveying chute 13 and this latter chute 13 is preferably mounted on a raft or other floating member, and, by reason of the pivotal connection with the refuse trough, it may be turned in the desired direction so that the refuse is deposited in a place away from the dredging ground, or onto a raft or other conveyance if desired.

Both the washing chute 9 and the refuse trough 10 are mounted in supports 20, preferably by means of a pivot 21, and the receiving ends of these members are held between uprights 22 which are in turn provided with elongated slots 24, so that the opposite ends of the members 9 and 10, may be raised until the tubular connections are made at 11, after which they are secured in any suitable manner.

The mouth of the pump tube 8 is directed

into the receiving end of the washing chute 9 and the culm will pass down this chute, depositing the refuse and water into the refuse trough 10 and deliver the reclaimed coal 5 through the pivotal tubular connection 11 into the end of the chute or trough 5 where it is engaged by the vanes on the elevator belt and carried to the top of the trough and deposited on the wharf or on cars as de-
10 sired.

It is evident that with this invention, I am enabled to work over a relatively large space of river bottom without changing the delivery point of the reclaimed coal.

15 The invention is simple in construction, low in cost, and particularly well adapted to the work described.

What I claim is:—

1. In a device of the character described, 20 a stationary float, an elevating device thereon, a trough in which the elevating device moves, said trough having an upwardly projecting hollow member at one end; a movable float, a suction pump located thereon, 25 a washing chute pivotally mounted on the float and into which the pump deposits the dredging, means for raising and lowering the delivery end of said washing chute, said chute having a downwardly projecting hollow member adapted to enter the hollow member on the trough of the stationary

float, a refuse trough located immediately beneath said chute, said refuse trough being pivotally mounted on the float and having means for raising and lowering the delivery 35 end of the trough, a downwardly projecting hollow member on the delivery end of said refuse trough, a conveying chute, an upwardly projecting hollow member on the receiving end of said conveying chute adapted 40 to receive the like member on the refuse trough, and a float for said conveying chute.

2. In a device of the character described, a stationary float, an elevating device thereon, a trough in which the elevating device 45 moves, said trough having an upwardly projecting hollow member at one end; a movable float, a dredging pump thereon, a chute into which the pump deposits the dredging, said chute having a downwardly projecting 50 hollow member adapted to enter the hollow member on the trough of the stationary float, a refuse trough located immediately beneath the chute, a downwardly projecting hollow member on the end of said refuse 55 trough, a conveying chute, an upwardly projecting hollow member on said conveying chute adapted to receive the like member on the refuse trough, and a float for said conveying chute.

In testimony whereof I affix my signature.
GRANT E. ALLEMAN.
